UNITED STATES PATENT OFFICE.

JOHN T. PEARSON AND RAYMOND H. OLLEY, OF SYRACUSE, NEW YORK, ASSIGNEES
TO CROUSE-HINDS COMPANY, OF SYRACUSE, NEW YORK, A CORPORATION OF NEW
YORK.

COVER FOR ELECTRIC OUTLET BOXES.

Application filed September 27, 1922, Serial No. 590,764. Renewed December 10, 1924.

This invention has for its object a cover for electric outlet boxes, as conduit outlet boxes, having an open side, which cover is provided with an outlet for the electric wires 5 and a particularly simple, efficient and durable construction and arrangement of a self-contained means for securing the cover to the box of the general type set forth in our Patent No. 1,525,684, issued February 10, 1925.

The invention consists in the novel features and in the combinations and constructions hereinafter set forth and claimed.

In describing this invention, reference is 15 had to the accompanying drawings, in which like characters designate corresponding parts in all the views.

Figure 1 is an elevation, partly in section, of a conduit outlet box provided with our 20 cover.

Figure 2 is an inner face view of the cover.

Figure 3 is a sectional view on line 3—3 Fig. 1.

1 designates the outlet box, which may be 25 of any suitable form, size and construction, it being here shown as provided with one or more nipples 2 for connection to the conduits enclosing the service wires and with an opening 3 in one side. The opening is preferably elongated and bounded by opposing parallel side walls 4 and rounding end walls 5. 6 designates the cover which comprises a body 7 and a plate 8 on the inner side of the body, the plate having its ends secured 30 to the inner face of the body 7 and its intermediate portion 9 offset or spaced apart from the body. The body 7 is here shown as a plate and the plate 8 is of the same general form in plan, but of less dimensions 35 than the body 7, leaving a marginal bearing face 9 on the inner face of the body, which rests on the edge of the walls 4, 5, bounding the opening 3, and the plate 8 fits into such opening. The plate 8 is secured to the 40 body 7 in any suitable manner, as by spot welding, indicated at 8^a, Fig. 2.

The intermediate portion 9 of the plate 45 and the body 7 are formed with aligned holes, and a nipple 10 extends through such aligned holes and is spread or riveted at its inner end at 11 on the intermediate portion 9 of the plate 8 and is provided with an annular shoulder 12 abutting against the outer face of the body 7.

Owing to the rivet head or shoulder 11

and the shoulder 12, the nipple is clamped to the intermediate portion 9 of the plate and to the body 7.

The wires from the outlet box are led through this nipple and also the nipple is 60 screw-threaded to support a fixture or any other appliance.

In order to stiffen the cover to support the nipple and the weight applied thereto, or to the wires or fixtures supported by the 65 nipple, a brace is inserted between the intermediate portion 9 of the plate 8 and the inner face of the body 7 and as here shown, the intermediate portion 9 is provided with a flange 13 along one edge thereof which 70 flange meets the inner face of the body 7.

One edge 14 of the intermediate portion is projected outwardly in position to engage and thrust against the inner face of the opposing wall 4 of the box, such edge 14 being 75 on the opposite side of the intermediate portion from that on which the flange 13 is located, and means, as wedges 15, are located on the side of the intermediate portion on which the brace 13 is located, these 80 wedges being arranged at the ends of the flange 13, which flange terminates short of the ends of the intermediate portion 9. Also the wedges are located on opposite sides of the nipple 10. The wedges 15 are 85 here shown as located in slots 16 formed in the intermediate portion on opposite sides of the nipple, the wedges coacting at their inner ends with the end walls of the slots 90 and projecting slightly beyond the flange 13. 90

As here illustrated, the end walls of the slots 16 are formed inclined and also the engaging ends of each wedge are formed inclined so that when the wedge is moved toward the body, the face of the wedge and the inclined face of the end wall of the slot 16 act inclined plane fashion on each other and cause the wedge 15 to be thrust outwardly against the inner face of the wall of the box. 100

As here illustrated, the end wall of each slot is formed by a tongue 17 struck from the intermediate portion 9 and extended toward the inner face of the body 7.

Each wedge 15 is operated by means operable from the outer side of the body 7, this means being a screw 18 extending through the body 7 and threading into the wedge member 15. 105

The hole in the body 7 for the screw 18 110

is a slot 20 which permits the screw to move without tilting during tightening of the screw and movement of the wedge outwardly. The opposing faces of the box engaged by the edge 14 and by the wedges 15 are beveled so that the cover is secured to the box by what in effect is a dove-tailed joint. In operation, the cover is placed in the opening 3 after the wires have been drawn through the nipple 10 and the screws 18 tightened, thus causing the wedges to thrust against one side wall of the box and the edge 14 to thrust against the opposite side wall.

Owing to the arrangement of the wedges relatively to the nipple and to the brace 13, the cover is secured in position and is braced to carry any weight that may be applied to the nipple 10.

What we claim is:—

1. A cover for electric outlet boxes having an opening in one side, the cover comprising a body and a plate on the inner face of the body having its ends secured to the inner face of the body and its intermediate portion offset and spaced apart from the body, the body and said intermediate portion having alined holes therethrough, and a nipple extending through said holes and secured to the intermediate portion of the plate, substantially as and for the purpose described.

2. A cover for electric outlet boxes having an opening in one side, the cover comprising a body and a plate on the inner face of the body having its ends secured to the inner face of the body and its intermediate portion offset and spaced apart from the body, the body and said intermediate portion having alined holes therethrough, and a nipple extending through said holes and secured to the intermediate portion of the plate, and having a shoulder abutting against the outer face of the body, substantially as and for the purpose specified.

3. A cover for electric outlet boxes having an opening in one side, the cover comprising a body and a plate on the inner face of the body having its ends secured to the inner face of the body and its intermediate portion offset and spaced apart from the body, the body and said intermediate portion having alined holes therethrough, and a nipple extending through said holes, the nipple having shoulders abutting against the outer face of the body and the inner face of said intermediate portion, substantially as and for the purpose set forth.

4. A cover for electric outlet boxes having an opening in one side, the cover comprising a body and a plate on the inner face of the body having its ends secured to the inner face of the body and its intermediate portion offset and spaced apart from the body, the body and said intermediate por-

tion having alined holes therethrough, a nipple extending through said holes and secured to the intermediate portion of the plate and a brace between said intermediate portion and the body, substantially as and for the purpose described.

5. A cover for electric outlet boxes having an opening in one side, the cover comprising a body and a plate on the inner face of the body having its ends secured to the inner face of the body and its intermediate portion offset and spaced apart from the body, the body and said intermediate portion having alined holes therethrough, and a nipple extending through said holes and secured to the intermediate portion of the plate, said intermediate portion having a flange along one edge thereof meeting the inner face of the body and constituting a brace, substantially as and for the purpose specified.

6. A cover for electric outlet boxes having an opening in one side, the cover comprising a body and a plate on the inner face of the body and having its ends secured to the inner face of the body and its intermediate portion offset and spaced apart from the body, the body and said intermediate portion having alined holes therethrough, and a nipple extending through said holes and secured to the intermediate portion of the plate, said intermediate portion having a flange along one edge thereof meeting the inner face of the body and constituting a brace, and said intermediate portion also having its edge on the side thereof opposite the flange arranged to thrust against the inner face of one of the side walls of the box, substantially as and for the purpose set forth.

7. A cover for electric outlet boxes having an opening in one side, the cover comprising a body and a plate on the inner face of the body and having its ends secured to the inner face of the body and its intermediate portion offset and spaced apart from the body, the body and said intermediate portion having alined holes therethrough, a nipple extending through said holes and secured to the intermediate portion of the plate, said intermediate portion having a flange along one edge thereof meeting the inner face of the body and constituting a brace, and said intermediate portion also having its edge on the side thereof opposite the flange arranged to thrust against the inner face of one of the side walls of the box, and means coacting with the intermediate portion and the opposing inner face of the box for thrusting such edge against the opposite inner face of the box and securing the cover to the box, substantially as and for the purpose described.

8. A cover for electric outlet boxes having an opening in one side, the cover comprising

- a body and a plate on the inner face of the body having its ends secured to the inner face and its intermediate portion offset and spaced apart from the body, the body and said intermediate portion having aligned holes therethrough, a nipple extending through the holes and secured to the plate, one edge of the plate being arranged to engage the inner face of one of the side walls of the box and wedging means located at the opposite edge of such intermediate portion and coacting therewith and with the inner face of the opposing wall of the box to secure the cover to the box, and operating means for the wedging means extending through the cover and operable from the outer side thereof, said wedging means being located on opposite sides of the nipple, substantially as and for the purpose specified.
9. A cover for electric outlet boxes having an opening in one side, the cover comprising a body and a plate on the inner face of the body having its ends secured to the inner face of the body and its intermediate portion offset and spaced apart from the body, the body and said intermediate portion having aligned holes therethrough, a nipple extending through said holes and secured to the intermediate portion of the plate, said intermediate portion having an edge arranged to thrust against the inner face of the opposing wall of the box and a flange on the opposite edge thereof, meeting the inner face of the body and constituting a brace, said flange terminating short of the ends of the intermediate portion and on opposite sides of the nipple, wedging members coacting with the intermediate portion at opposite ends of the flange and operating to thrust against the inner face of the opposing wall of the box and means for operating the wedge members from the outer side of the body, substantially as and for the purpose set forth.
10. In combination with an electric outlet box, having an opening in one side, a cover, a plate having its ends secured to the inner face of the cover and its intermediate portion offset and spaced from the cover, said cover and said plate having aligned holes therethrough, a nipple extending through said holes and secured to the intermediate portion of the plate, said intermediate portion having a flange along one edge

thereof meeting the inner face of the cover and constituting a brace, and said intermediate portion also having its edge on the side thereof opposite the brace flange arranged to thrust against the inner face of one of the side walls of the box, and means coacting with the plate and the opposing inner face of the box for thrusting such edge against the opposite inner face of the box and securing the cover to the box.

11. In combination with an electric outlet box, having an opening in one side, a cover, a plate having its ends secured to the inner face of the cover and its intermediate portion offset and spaced from the cover, said cover and spaced plate having aligned holes therethrough, a nipple extending through the holes and secured to the plate, one edge of the plate being arranged to engage the inner face of one of the side walls of the box, wedging means located at the opposite edge of such intermediate portion and coacting therewith and with the inner face of the opposing wall of the box to secure the cover to the box, and operating means for the wedging means extending through the cover and operable from the outer side thereof, said wedging means being located on opposite sides of the nipple.

12. In combination with an electric outlet box, having an opening in one side, a cover, a plate having its ends secured to the inner face of the cover and its intermediate portion offset and spaced from the cover, said intermediate portion having one edge arranged to thrust against the inner face of the opposing wall of the box and a flange on the opposite edge thereof engaging the inner face of the cover and constituting a brace, said flange terminating short of the ends of the intermediate portion, bevelled surfaces formed on said plate at the ends of said flange, a nipple secured in said cover, wedging members coacting with the bevelled surfaces at the end of the flange and operating to thrust against the inner face of the opposing wall of the box, and means for operating the wedge members from the outer side of the cover.

In testimony whereof, we have hereunto signed our names, at Syracuse, in the county of Onondaga, and State of New York, this 18th day of September, 1922.

JOHN T. PEARSON.
RAYMOND H. OLLEY.
